T. N. RUSSELL

CARLINE

Filed March 13, 1920

Inventor
Thomas Nathan Russell
By Munder, Clarke &
Carpenter, his Atty's.

UNITED STATES PATENT OFFICE.

THOMAS NATHAN RUSSELL, OF CHICAGO, ILLINOIS, ASSIGNOR, BY MESNE ASSIGNMENTS, TO CHICAGO-CLEVELAND CAR ROOFING COMPANY, OF CHICAGO, ILLINOIS, A CORPORATION OF DELAWARE.

CARLINE.

Application filed March 13, 1920. Serial No. 365,478.

This invention relates to carlines more particularly designed for use in freight car roof frames, and has for an object the provision of a simply constructed, though 5 strongly braced carline that is reinforced at the points of attachment to the side frame members or side plates, with the result of making the carline, as a whole, stronger for the resistance of all vertical, horizontal and 10 torsional strains, and of preventing a hinge action at the points where the carline is secured to the side frame members or plates. The invention has for further objects a general stiffening and reinforcing of the roof 15 frame, and such other improvements or advantages in construction and operation as are found to obtain in the structures and devices hereinafter described or claimed.

In the accompanying drawings, forming 20 a part of this specification, and showing, for purposes of exemplification a preferred form and manner in which the invention may be embodied and practiced, but without limiting the claimed invention specifically to such 25 illustrative instance or instances:

Figure 1 is a vertical transverse section of a portion of a car roof frame provided with a carline embodying the invention, and showing said frame and the sheathing in 30 section and the carline partly in section and partly in elevation;

Fig. 2 is a plan view of the same;

Fig. 3 is a perspective view of an end portion of the carline;

Fig. 4 is a vertical transverse section of the carline taken on the line 4—4 of Fig. 2, and

Fig. 5 is another vertical transverse section of the carline taken on the line 5—5 of Fig. 2.

The same characters of reference indicate the same parts throughout the several views.

Referring to the drawings, there is indicated at 11 the side plates of the roof frame, 45 suitably secured as shown at 12 to side poles 13, there being a plurality of such poles disposed at intervals along each side of the car. Mounted on the upper end of the rows of side poles 13 are longitudinally extending 50 Z-bars 14, the vertical webs 15 of which are suitably secured as shown at 16 to the side plates 11. The top horizontal flanges 17 of the aforesaid Z-bars 14 respectively extend laterally inwardly from the inside faces of

the side plates 11, see Fig. 1, whereas the 55 bottom horizontal flanges 18 of said Z-bars extend laterally outwardly from said side plates 11 and rest on the upper ends of the side poles 13. As shown in Fig. 1, the ridge pole is indicated at 19 and the purlins at 20. 60

The carline 21 consists of a single steel bar formed with a central upstanding rib 22 of inverted U-shape, that extends from end to end of the carline. This central rib 22 tapers down laterally from a point adjacent the apex 23 of the carline to the ends 24, as shown in Fig. 1. The horizontal side flanges 25 of the carline may taper inwardly toward the longitudinal center of the carline, as shown at 26. Toward the side plates 70 11 of the car roof frame, the side carline flanges 25, which extend oppositely from the central reinforcing rib 22, are bent upwardly as shown at 27 to form vertical stiffening flanges 28 situated at the opposite 75 ends of the carline, and these stiffening flanges 28 may taper downwardly from the opposite ends of the carline toward its longitudinal center and into the side flanges 25, as indicated at 29 in Fig. 1. The central 80 rib 22, which is relatively lower at the ends of the carline than at its apex, is thus reinforced at the opposite carline ends by means of vertical flanges that extend parallel with said central rib along its opposite sides. 85

Further reinforcing of the opposite ends of the carline is effected by bending the horizontal flanges 25 and the central rib 22 downwardly, as shown at 30, so that these flanges 25 and rib 22 overlap, as shown at 90 32 the vertical web 15 of the Z-bar 14. The opposite ends of the carline are suitably secured to the frame by bolts or rivets 31 passed through the carline flanges 25 and the top horizontal flanges 17 of the Z-bars 95 14. By bending the opposite ends of the carline downwardly, so that they overlap or overlie the side frame members, such as the Z-bars hereinabove mentioned, an important reinforcing effect is attained at the 100 points of attachment of the carline to the side frame members, which reinforcing effect eliminates any tendency to a hinge action at these points. This reinforcement is of great importance because severe strains 105 and stresses are brought to bear on the side members and carline ends at the points of attachment, especially when the car is tilted

while turning curves, such stresses tending to effect a relative movement of the carlines and side members and to rip the fastenings apart or bend the parts out of their true 5 relative positions.

The invention as hereinabove set forth is embodied in a particular form of construction but may be variously embodied within the scope of the claims hereinafter made.

10 I claim:

1. In a car roof, in combination: a roof frame including side Z-bars secured to the side members of said frame and having their top horizontal flanges extended inwardly beyond the inner faces of said side members; a carline extended between said Z-bars and constituted of a single steel bar formed with a central upstanding reinforcing rib that extends from end to end of the carline and tapers downwardly from the apex thereof to its opposite end, and with side horizontal flanges extending along the opposite sides of said reinforcing rib, the aforesaid rib and side flanges being bent downwardly at the opposite ends of the carline over against the outer faces of the vertical webs of the aforesaid Z-bars; and means for securing the horizontal flanges of said carline to the top horizontal flanges of said Z-bars, substantially as specified.

2. A carline comprising a rigidifying rib of constant width having sides decreasing in depth from the ridge portion toward each

end, said sides terminating in lateral flanges increasing in width as the sides decrease in 35 depth, said lateral flanges being bent transversely from a point back of the eaves towards the eaves.

3. A carline comprising a central rigidifying rib of constant width from end to end 40 and having sides decreasing in depth toward the eaves from a point at each side of the ridge, said carline being of constant width from a point short of the eaves toward the eaves, said sides having lateral flanges, a 45 portion of the flanges increasing in width toward the eaves and a portion of the material of said lateral flanges being struck upwardly from said point short of the eaves out to the eaves ends of said carline. 50

4. A carline comprising a rigidifying rib of constant width having sides terminating in lateral flanges in a common plane, said sides decreasing in height from the ridge toward the eaves and said lateral flanges 55 increasing in width toward the eaves, a portion of said lateral flanges at each eaves end being flanged upwardly.

5. A carline comprising a rigidifying rib having sides decreasing in depth toward the 60 eaves from a point adjacent the ridge, said sides having flanges, portions of the flanges being bent upwardly, said portions decreasing in depth toward the ridge from a point adjacent the eaves end of the carline.

THOMAS NATHAN RUSSELL.
